UNITED STATES PATENT OFFICE.

ROBERT L. WRIGHT, OF SAN ANTONIO, TEXAS.

COOLING DEVICE FOR LARD-COMPOUNDING MACHINES.

No. 888,680.

Specification of Letters Patent.

Patented May 26, 1908.

Application filed December 29, 1906. Serial No. 350,027.

To all whom it may concern:

Be it known that I, ROBERT L. WRIGHT, a citizen of the United States of America, and a resident of San Antonio, in the county of 5 Bexar and State of Texas, have invented certain new and useful Improvements in Cooling Devices for Lard-Compounding Machines, of which the following is a specification.

10 My invention relates to improvements in lard compounding machines in which the melted lard compound is spread on a rotating drum and scraped off in thin layers. In the rotating drum is located a smaller stationary drum which consists of two galvanized sheet iron end disks with an opening in one, and connected in their periphery by iron rods, and the drum so formed is covered by galvanized iron netting. On the inside 15 of the rotating drum are several longitudinal buckets for carrying up the brine which is poured on the inner surface of the rotating drum.

The object of my invention is to spread 25 the melted lard compound on a large surface, in thin sheets, and by freezing quickly the melted lard compound is thoroughly unified. I attain this object by the machine illustrated in the accompanying drawing in 30 which—

Figure 1 is a longitudinal section of the entire machine, and Fig. 2 is an end view of the same, without the lard compound receptacle, showing the rotating drum in section. 35 Fig. 3 is a separate view of a longitudinal bucket S, showing the side and end.

Similar letters and figures refer to similar parts throughout the several views.

A, is a receptacle of galvanized iron or 40 other suitable material, with an outlet valve B, for the reception of melted lard compound. This receptacle A, has a jacket A¹, with a pipe inlet A², and a pipe outlet A³. The valve B, is connected with a pipe D, 45 which runs in its entire length through a tube C. This tube is closed at both ends and forms a water jacket. The tube C, has also a pipe inlet C¹, and a pipe outlet C², and the pipe outlet A³, of the jacket A¹, is connected by pipe C³, with the pipe inlet C¹, of the tube C. The pipe inlet A², and the pipe 50 outlet C², are connected with a suitable water heater—not shown in the drawing—so that the hot water circulates from the water heater into the jacket A¹, of the receptacle, 55 from there into the jacket C, of the pipe, and

from there back into the water heater. By this means the lard compound is kept in a melted state in the receptacle A, and while passing through the pipe D, to the outlet D¹. 60 From time to time the lard compound in the receptacle is thoroughly stirred to keep the lard compound well mixed. The outlet D¹, is placed over the middle of a strainer trough E, which is located on top of the freezing 65 machine. This machine consists of a wooden frame F, on which is fastened two brackets G, which hold a shaft H. On this shaft H, is suitably fastened two galvanized sheet iron disks I, which are at their periphery connected with a number of galvanized iron rods K, the whole forming a drum. This drum is for the reception of ice and has in one disk I, an opening J, and the outer surface is covered with galvanized iron netting L, to keep 70 the small pieces of ice inside the drum. 75

A larger drum M, of galvanized iron, or other suitable materials inclosing the ice drum has journals N, at the ends whereby the drum revolves on the shaft H. The one 80 end disk has a door O, corresponding in size and location with the opening J, of the ice drum. To the one journal N, is fastened a sprocket wheel P. On the frame F, is located a driving sprocket wheel Q, which 85 carries on its shaft a crank R, and the sprocket wheels are connected by an endless chain. Inside of the drum M, are fastened three or more longitudinal buckets S, which are perforated at their bottoms. When the 90 ice drum is filled with ice the drum M, is partly filled with brine. The buckets S, will spread the brine against the inner surface of the drum when the crank is turned. A scraper T, is pressed by means of springs 95 U, against the outside of the drum, and a large receptacle V, is placed underneath. To operate the machine the melted lard compound is let into the perforated trough E, by the pipe outlet D¹, and is spread in 100 thin layers on the surface of the drum, and freezes immediately, and is then scraped off by the scraper T, and dropped in the receptacle V.

Having now fully described my invention 105 what I claim as my invention and desire to secure by Letters Patent is—

1. In a machine of the type set forth, an outer drum, a plurality of inwardly extending buckets right angular in cross section 110 carried by said drum, an inner drum in said outer drum composed of end disks, a series

of rods connecting said disks at their periphery and netting overlying said rods and the disk peripheries.

2. In a machine of the type set forth, an outer drum, a series of inwardly extending buckets L-shape in cross section carried by said drum so that the base of the L will be innermost and the vertical leg thereof disposed radially of said drum, an inner drum

composed of end disks, connecting means 10 for the disks, and mesh material surrounding said disks.

Signed at San Antonio, Texas, this 17 day of Dec. 1906.

ROBERT L. WRIGHT.
